(57) **CLAIM**

The ornamental design for a tablet PC support device, as shown and described.

DESCRIPTION

FIG. 1 is a front view of the present invention; and FIG. 2 is a rear view of the present invention; and FIG. 3 is a right side view of the present invention; and FIG. 4 is a left side view of the present invention; and FIG. 5 is a top view of the present invention engaged with a user; and

FIG. 6 is a bottom view of the present invention; and, FIG. 7 is a perspective view of the present invention, but shown in an alternate rotated position.

The superimposed broken lines are included for the purpose of showing use and environment and form no part of the claimed design.
